UNITED STATES PATENT OFFICE.

ARNOLD CREMONINI, OF FORT BRAGG, CALIFORNIA.

SQUARE-HOLE-DRILLING DEVICE.

Application filed December 19, 1922. Serial No. 607,913.

To all whom it may concern:

Be it known that I, ARNOLD CREMONINI, a citizen of the United States, residing at Fort Bragg, in the county of Mendocino and

5 State of California, have invented certain new and useful Improvements in Square-Hole-Drilling Devices, of which the following is a specification.

This invention relates to square hole drilling devices and more particularly to work holders therefor.

An object of the invention is the provision of a compact work holder for square hole drilling which may be readily attached to 15 the bed plate of a machine and will securely hold the article being bored.

A further object of the invention is to provide a work holder having adjusting means whereby it may be readily changed 20 to receive articles of different sizes.

A further object is the provision of an adjustable guide to be mounted in the work holder which may also be adjusted when articles of different sizes are being bored.

25 In the accompanying drawings, I have shown one embodiment of the invention. In this showing:

Figure 1 is a perspective view of a portion of a machine showing the invention applied,

Figure 2 is a central vertical sectional view of the work holder,

Figure 3 is a horizontal sectional view on line 3—3 of Figure 2,

25 Figure 4 is a vertical sectional view on line 4—4 of Figure 2,

Figure 5 is a similar view on line 5—5 of Figure 2,

Figure 6 is an end view of the boring 40 tool or bit,

Figure 7 is a side elevation of the tool, and,

Figure 8 is a detail view of one of the clamping elements.

45 Referring to the drawings, the reference numeral 1 designates the bed plate of a boring machine or drill press upon which the work to be bored is adapted to be supported. A tool holder 2 is mounted above the bed

50 plate and is adapted to be lowered in any suitable manner. A bit 3 is arranged in the tool holder in any suitable manner. As shown, (see Figures 6 and 7), the bit is substantially triangular in cross section and 55 is provided with cutting edges 4.

The work holder forming the subject

matter of the present invention consists of a pair of substantially U-shaped members 5, which are adapted to be clamped to the bed plate of the machine by bolts 6, passing 60 through suitable openings in the clamping members. These bolts are adapted to receive nuts 7 to retain them in position. As shown, one of the arms of each of the U-shaped members is provided with an enlargement 8 at its outer end, forming a substantially solid block through which the bolt passes. The face of one of the U-shaped members is roughened, as at 9, and is adapted to form a clamping surface to engage the article being bored. The block 8 of the other member is surrounded by a substantially U-shaped clamping jaw 10 having a roughened or serrated face 11 adapted to engage the article being bored. A similar 70 member 12 is arranged over the clamping member 10 with the bases of the U extending in the opposite direction. A bolt 13 passes through an opening in the supporting member 5 and engages the U-shaped 80 member 12 to permit adjustment of the space between the clamping faces 9 and 11.

A guide plate 14 is mounted over the space between the clamping faces and is provided with a guide opening 15. This 85 member extends into the supporting members 5 and is provided with longitudinal slots 16 to receive the bolts 6.

The operation of the device will be apparent from the foregoing description. The 90 supporting members 5 are first adjusted to receive the work and the guide member 14 is arranged in proper position by adjusting the bolts 6 in the slots 16. After the work holder has been roughly adjusted, it is tightened by the bolt 13 which feeds the members 10 and 12 toward the work and causes the clamping faces 9 and 11 to firmly engage it.

It is to be understood that the form of 100 my invention herewith shown and described is to be taken as a preferred example of the same, and that various changes in the shape, size, and arrangement of parts may be resorted to without departing from the spirit 105 of the invention or the scope of the subjoined claims.

Having thus described my invention, I claim:

1. A work support and drill guide for 110 drills of the non-circular cut type, comprising two independent members fastened to

the machine table, one providing a stationary jaw and the other carrying a movable clamping jaw, and a drill guide immovably fastened to each of said members with the 5 drill guiding portion positioned between the jaw portions thereof.

2. A work holder and drill guide for drills of the non-circular cut type, comprising a pair of supporting members, a bolt 10 arranged in each of said supporting members to adjustably secure it to the bed plate of a machine, one of said members being provided with a stationary clamping jaw, a movable clamping jaw carried by the other 15 member, said jaw comprising a pair of

U-shaped members, one of which is inverted and arranged within the other, a threaded rod carried by said supporting member and engaging the base of one of said U-shaped members, and a guide arranged above said clamping jaws, said guide being provided with a pair of elongated slots to receive 20 said bolts.

In testimony whereof, I affix my signature in presence of two witnesses.

ARNOLD CREMONINI
